United States Patent Office

Des. 185,585
Patented June 23, 1959

185,585

TABLE OR SIMILAR ARTICLE

Carl W. Sundberg, Bloomfield Hills, Mich., assignor to Whirlpool Corporation, St. Joseph, Mich., a corporation of Delaware

Application April 29, 1957, Serial No. 45,937

Term of patent 14 years

(Cl. D33—14)

Figure 1 is a perspective view of a table or similar article, showing my new design;

I claim:

The ornamental design for a table or similar article, as shown.
